(57) **CLAIM**

The ornamental design for an electronic drum set, as shown and described.

DESCRIPTION

FIG. 1 is a front, top perspective view of an electronic drum set, showing my new design;

FIG. 2 is a rear, bottom perspective view thereof;

FIG. 3 is a front elevation view thereof;

FIG. 4 is a rear elevation view thereof;

FIG. 5 is an enlarged left side elevation view thereof;

FIG. 6 is an enlarged right side elevation view thereof;

FIG. 7 is an enlarged top plan view thereof;

FIG. 8 is an enlarged bottom plan view thereof;

FIG. 9 is an enlarged, partial view taken at line-9 in FIG. 1;

FIG. 10 is an enlarged, partial view taken at line-10 in FIG. 1;

FIG. 11 is an enlarged, partial view taken at line-11 in FIG. 1;

FIG. 12 is an enlarged, partial view taken at line-12 in FIG. 1;

FIG. 13 is an enlarged, partial view taken at line-13 in FIG. 1; and,

FIG. 14 is an enlarged, partial view taken at line-14 in FIG. 2.

The dashed lines in the figures illustrate portions of the electronic drum set that form no part of the claimed design. The dash dot dash lines in FIGS. 1, 2, 9, 10, 11, 12, 13 and 14 are for the purpose of illustrating the enlarged views indicators and form no part of the claimed design.

1 Claim, 14 Drawing Sheets
